UNITED STATES PATENT OFFICE.

ROBERT M. CAMPBELL AND LAWRENCE S. CAMPBELL, OF LOS ANGELES, CALIFORNIA.

AUTOMATICALLY-CONTROLLED GATE.

1,215,906.

Specification of Letters Patent. Patented Feb. 13, 1917.

Application filed December 1, 1915. Serial No. 64,450.

To all whom it may concern:

Be it known that we, ROBERT M. CAMPBELL and LAWRENCE S. CAMPBELL, citizens of the United States and the Dominion of Canada, respectively, residing at Los Angeles, in the county of Los Angeles and State of California, have invented new and useful Improvements in Automatically-Controlled Gates, of which the following is a specification.

This invention relates to an automatically controlled gate, and pertains especially to gates of the turnstile type.

This invention is especially adapted to gates controlling the entrance of persons to an auditorium such as a theater, and it is an object of this invention to provide a gate mechanism in co-operation with an admission accumulator, whereby the operation of the accumulator will first unlock the gate to permit the entrance of any selected number of persons; and second, will automatically lock the gate after entrance of that number.

A further object is to provide a gate construction which may be opened from within in such a manner that there will be no obstruction in the passageway it controls, the gate being merely opened by a push from within. This latter feature is valuable to permit the exit of persons at the time of a fire or panic.

We accomplish the above objects by means of the embodiment of our invention illustrated in the accompanying drawing, in which:

Figure 1 is an elevation of our improved gate.

Fig. 2 is a plan view.

Fig. 3 is an enlarged vertical section as seen on the line 3—3 of Fig. 2.

Fig. 4 is a horizontal section as seen on the line 4—4 of Fig. 3.

Fig. 5 is a plan view of a detail.

Fig. 6 is a section as seen on the line 6—6 of Fig. 3, with parts in plan view.

Fig. 7 is a plan view of the trailer detail.

Fig. 8 is a development in elevation of the trailer detail shown in Fig. 7.

Fig. 9 is a fragmentary development showing the trailers in another position.

Fig. 10 is an enlarged elevation of a motor control switch.

Fig. 11 is an elevation of the gate control mechanism.

Fig. 12 is a section as seen on the line 12—12 of Fig. 11.

Fig. 13 is a fragmentary section as seen on the line 13—13 of Fig. 11.

Fig. 14 is a wiring diagram of the electric connections of the system.

Referring more particularly to Figs. 1 and 2, a pillar or post 14 of suitable construction and material, such as polished brass, is disposed vertically at one side of the entrance of the auditorium, and suitably secured to the floor by foot member 15. Mounted upon the post 14 for pivotal movement is a turnstile supporting arm 16 which carries at one end the turnstile mechanism indicated generally by 17. A reduced extension of the post 14 is indicated by 18 and may be carried to the ceiling, and a cross member 19 carried to the opposite side of the entrance. The post 18 and cross member 19 may be hollow and contain mechanism to operate other rails when the arm 16 is swung outward away from the entrance in the direction indicated by the arrow —a— in Fig. 2. Gate rails 20 and 21 are disposed upon the top of the turnstile mechanism 17 and are for the purpose of keeping the entrants within the bounds of a certain passageway.

The arm 16 is provided at its free end 23 with a housing section 22 having a boss 23 provided with a recess 24 to form a foot bearing for a shaft 25. Shaft 25 is normally stationary. Keyed to the upper end of the shaft is a disk 26. Disk 26 has a portion cut away as more particularly shown in Fig. 4. Rotatably mounted upon shaft 25 is a sleeve 27 which has fixedly secured to it a circular plate 28. Rotatably mounted upon sleeve 27 is a turnstile arm 29 which in the position shown is a leading arm. A second turnstile arm 30 is relatively mounted on sleeve 27 and in the position shown is a following arm. Arms 29 and 30 at their bearings upon sleeve 27 are constructed with one bearing, off-set with respect to the other so that arms 29 and 30 move in the same plane.

A disk 31 is rotatably mounted upon the sleeve 27 and below the bearings for arms 29 and 30. Disk 31 is provided with a later-

ally extending flange 32. A housing section 33 is provided to coöperate with the housing section 22 and has a flange which is disposed to overlap the cylindrical wall of housing section 22. At the center of the housing section 33 is a boss 34 having an aperture through which extends the sleeve 27 and to which the latter is keyed as indicated at 35. A thrust bearing 36 is mounted in the boss and supports the disk 31 and the arms 29 and 30.

Each arm is provided with a trailer of segmental form 29' and 30', as more particularly shown in Figs. 7, 8 and 9. The 15 trailers are duplicates and are provided at their noses 37 and 37' with notches 38 and 38'. Each notch has a lower wedge wall as shown at 39 and 39' and an upper recess as indicated at 40 and 40'. The tails 41 and 20 41' of each trailer have depending catches indicated by 42 and 42' forming shoulders and tapered parts 43 and 43'. Laterally extending lugs 44 and 44' are provided at the tips of the tails 41 and 41'. The tails are 25 reduced in thickness, as indicated at 45 and 45' and at the noses as indicated by 46 and 46', the mean diameter at the tail portion being less than the mean diameter at the nose portion so that the nose and the tail 30 will overlap when brought together.

A track 47 for the trailers is formed on the housing section 33 and may be integral therewith or a separate part, if desired. It forms in effect an annular cam with a raised 35 portion as indicated at 47'. The raised portion extends substantially half way around the entire track and has a notch 49 at its center which corresponds in form to the catches 42 and 42' on the tails of the trailers.

40 Ratchet teeth 50 are formed on one portion of the track and are adapted to be engaged by either pawl 51 or 52, the latter being pivotally mounted on trailers 29' and 30' and preventing retrograde movement of 45 the leading trailer. A trailer releasing arm 53 is pivotally mounted on sleeve 27. At the end of the arm 53 is an upstanding post 54, which has a tapered surface, as indicated at 55.

50 Referring particularly to Fig. 9, assume that arm 29 and trailer 29' have reached the position shown with the catch 42 disposed in notch 49, thereby locking the trailer 29' and arm 29 against forward movement in the 55 direction of arrow —c—. If arm 30 is moved toward arm 29 into the position shown in Figs. 7 and 8, the inclined surface 39' at the nose 37' of trailer 30' will ride under the inclined surface 43 of the tail 41 of trailer 29' lifting tail 41 and the catch 42 out of the notch 49 and hooking the lug 44 into the notch 38' in the nose 37', thereby locking trailer 29' to trailer 30' so that if 60 arm 29 is pushed forward it will carry arm 30 with it. In the position shown in Figs.

7 and 8, arms 29 and 30 are locked against movement in the direction of arrow —c—, as the catch 42' is engaged with the shoulder 48 on the raised portion 47' of track 47. In order to release the arm it is necessary to 70 raise the tail 41' of trailer 30'. This is accomplished by the post 54. If arm 53 is moved so that post 54 moves in the direction indicated by arrow —b— in Fig. 8, the tapered portion 55 will engage the depending portion 42' and raise the tail of trailer 30' above the shoulder 48 on the track clearing the latter so that the trailers and arms may be moved forward. As the trail 41 of trailer 29' reaches the ends of the raised 80 portion 47' of the track 47 the catch 42' on trailer 30' drops into notch 49 locking trailer 30'. In this position the tail 41 of trailer 29' will slide down the raised portion of the track 47 and release itself from notch 85 38' in the nose 37' of trailer 30'. Arm 29 may be moved the remainder of the distance finally locking with arm 30 in a similar manner to that shown in Figs. 7 and 8, arm 30 becoming the leading arm, arm 29 the following arm.

The unlocking movement of arm 53 is accomplished by means of a plunger 57 operated by a solenoid 56, the plunger 57 being pivotally connected to the arm 53 and the 95 spring 58 connecting the arm 53 to a stationary part of the casing and opposing the action of the solenoid 56.

In order to automatically move the turnstile arms after they have been started by 100 the person passing through the turnstile, we have shown the electric motor 61 having an extended shaft 62 with a friction wheel 63 at the end thereof. Wheel 63 is disposed in contact with the flange 32 so that operation 105 of the motor will cause a rotation of the disk 31. Rotatably mounted on each of the turnstile arms are rollers 64 and 65, the rollers being of a diameter such that they will contact the disks 26 and 31, so that rotation of the disk 31 will revolve the arms by rotating the rollers thereon, the latter rolling upon disk 26. The arms will cease to be moved by the motor when they reach the portion of the disk 26 which is cut away. 115 Thus, as shown in Fig. 4, when the arm 29 is moved by the entrant a sufficient distance for roller 64 to come in contact with disk 26, the motor being set in operation will move the arm 29 carrying with it the arm 30 until 120 the latter has moved one quarter of a revolution. When it unlocks from arm 29, continued operation of the motor will cause the arm 29 to continue to move until it reaches the other bounding edge of the cut away 125 portion of the disk whereupon the arm will stop, and at this time the motor stops.

The motor is controlled by a switch, particularly shown in Figs. 6 and 10, and indicated by 66. The switch consists of a 130

pivoted member 59 having contacts 68 and 60 electrically connected to a conductor 67 leading to one terminal of motor 61. Contacts 69 and 70 are connected to conductors 71 and 72 respectively. Conductor 72 is connected to a live side of the main current, see Fig. 14. The other terminal of the motor is connected to the other side of the circuit 74 by conductor 75. Conductor 71 connects with solenoid 106 hereinafter described. Switch 66 is operated by means of a link 66' pivotally connected to the lever 59 and connected at the ends to cranks 75 and 76 which are secured to pintles 77 and 78, having cranks 79 and 80 at their upper ends interposed in the path of pins which depend from the arms as indicated at 81 in Fig. 3. Pin 81 in its movement strikes crank 79 closing switch 66, making the circuit through conductor 72, contacts 69, 68, conductor 67, motor 61 and conductor 75, and causing the motor 61 to start moving. The arm 29 continues to move until pin 81 strikes arm 80 opening the switch 66 when the motor ceases to operate. In the movement of leading arm 29 from the position shown in Fig. 4, following arm 30 is locked to it through the trailers 29' and 30' and arm 30 will be carried with arm 29 through 90 degrees whereupon it becomes unlocked from arm 30 and locked to the track 47. The arm 29 continues its movement until the motion of its trailer locks with the tail of the trailer on arm 30, and arm 30 becomes the leading arm 35 and arm 29 the following. Energization of the solenoid 56 will unlock the arms and permit the entrance of another person.

Energization of the solenoid 56 is controlled by the accumulator mechanism shown in Figs. 11, 12 and 13. The accumulator mechanism may be disposed in the ticket office where it is operated by the cashier, or may be disposed at any other point, such as at the gate, a point which is convenient when tickets for reserved seats are used and the tickets are collected at the gate by a ticket taker.

A base plate 82 which may be fastened to a wall has mounted upon it a shaft 83. Rotatably mounted upon the shaft is a sleeve 84 to which is secured an admission storing member comprising a ratchet disk. Mounted upon posts 86 and 87 is a cross bar 88 which has an aperture at its center 89 in which is disposed the upper end of the shaft 83, thereby serving as a support for the latter. A pawl 90 engages the teeth on the storing disk 85 and is disposed for advancing the latter. Pawl 90 is held in engagement with the teeth by a spring 91 which is secured at one end to the plate 82 and at the other to the pawl. The pawl 90 is pivotally connected to a bell crank lever 93 which is pivotally mounted upon the plate 82 as indicated at 94. A link 95 is connected to the

lever 93 and an upward movement of the link will force the pawl forward, the movement being so designed that ratchet disk 85 will be moved one tooth. Link 95 is operated by the cashier and may be connected to a registering mechanism, such as is described in an application filed herewith of even date. Storing disk 85 is provided with a post 96 as particularly shown in Fig. 12. Secured to this post is a spiral spring 97, the inner end being connected to a post 98 which is mounted upon an admission discharge member 99 comprising an escapement disk.

Disk 99 is rotatably mounted upon sleeve 84 and its movement is controlled by an anchor 100 which engages with the teeth thereof. Movement of storing disk 85 winds spring 97 and tends to rotate disk 99. Anchor 100 is pivotally mounted upon post 87 and has an arm 101 which contacts with a cam 102. Cam 102 is provided with an arm 103 to which is pivotally connected a rod 104. Rod 104 is connected to the plunger 105 of a solenoid 106. Cam 102 is provided with a second arm 107 which is secured by a spring 108 to the plate 82. Spring 108 tends to maintain the cam in the position shown in Fig. 11.

Energization of the solenoid 106 pulls the plunger 105 inward, moves the cam 102 by 95 acting upon the rod 104 and arm 103, and lifts the arm 101 moving the anchor so that the discharge disk 99 may move one tooth. Upon the deenergization of solenoid 106 spring 108 acting upon arm 107 returns the 100 cam to the position shown in full lines, the arm 101 dropping by its own weight and locking the disk 99 through the anchor 100.

Fixedly secured to the discharge disk 99 is a collector 109. Collector 109 consists of 105 a disk of electric insulating material 110 provided with a peripheral groove 111. Mounted at the side walls of the peripheral groove 111 are annular rings 112 and 113 formed of electric conducting material. In 110 contact with ring 112 is a spring collecting brush 114 and in contact with ring 113 is a spring collecting brush 115. Brushes 114 and 115 are mounted upon an insulating block 116 which is secured to the base plate 115 82. Brush 114 is connected by a conductor 117 to one terminal of the solenoid 106. Brush 115 is connected to conductor 170 which leads to solenoid 56 which is mounted in the gate.

Referring particularly to Figs. 11 and 13, switch 118 is shown mounted upon collector disk 109 and comprises as shown in Fig. 13 spring jaws 119 and 120, jaw 119 being connected to ring 113 and jaw 120 being connected to ring 112. Pivots mounted upon disk 109 is a blade 121 whose free end is disposed to make electric contact with jaws 119 and 120. A spring 122' is secured to an ear on the blade 121, and to the col- 130

- lector disk 109 and tends to hold the blade 121 in the position shown in dotted lines in Fig. 13, so that the electric circuit between jaws 119 and 120 is closed.
- 5 Blade 121 is provided with an ear 122 which is adapted to be engaged by a lug 123 which is mounted upon a disk 124, the latter being rotatably mounted upon the sleeve 84. A lug 125 is mounted upon a disk 126 and abuts lugs 123. Disk 126 is rotatably mounted upon the sleeve 84. Keyed to the upper end of sleeve 84 is an arm 127 which extends radially, the end thereof being disposed to contact lug 125. Lugs 123, 125 and arms 127 are so disposed that they overlap so that as arm 127 rotates in a counter-clockwise direction it will engage lug 125 carrying disk 126 with it. Lug 125 will contact lug 123 carrying disk 124 with it.
- 10 Lug 123 will engage the ear 122 on blade 121 and pressure against ear 122 will move blade 121 into the position shown in full lines in Fig. 13, thereby breaking the circuit between jaws 119 and 120.
- 15 Assume that arm 127 is in the position shown in full lines in Fig. 13. If link 95 is moved upward it will move storing disk 85 through a distance of one tooth clockwise. The pawl 128 prevents retraction of the disk 85, spring 129 holding ratchet 128 in engagement with the disk. In the movement of the disk 85 in the clock-wise direction, spring 97 is placed under tension. As discharge disk 99 is held by the anchor 100 it maintains the post 98 to which the spring 97 is connected in a fixed position. Movement of the disk 85 moves sleeve 84 and arm 127 out of contact with lug 125, so that spring 122' will pull the blade 121 into engagement with the jaws 119 and 120, thereby closing the circuit. Since disks 124 and 126 are free to rotate upon the sleeve 84 they may be pushed forward by movement of the blade 121 and ear 122, as the arm 127 does not hinder movement of the disks. The circuit is closed and will remain closed until the escapement disk 99 is permitted to rotate in a clockwise direction. The spring 97 tends to rotate the escapement disk but is prevented from doing so by the anchor 100. If the anchor is moved, which may be accomplished by energizing the solenoid 106, the escapement wheel will be permitted to move one tooth. Movement of the escapement disk 99 in a clock-wise direction carries with it the blade 121. Ear 122 engages lug 123, which in turn engages lug 125 and arm 127, thereby moving the blade 121 inward into the position shown in full lines breaking the circuit between jaws 119 and 120.
- 20 If the link 95 is moved twice to move the ratchet disk 85 through two teeth, it will be necessary to operate the anchor twice before ear 122, lugs 123 and 125 engage the arm 127. Any number of movements of the es-

capement wheel may be stored up, thus if the arm 127 is moved into the position shown in dotted lines in Fig. 11 the anchor would have to be oscillated sixteen times before the blade 121 would break the circuit between jaws 119 and 120. It is obvious that admissions may be stored at the same time that they are being discharged. If the arm 127 was moved to make a complete revolution it would engage the lug 125 and carry it forward. It would then be necessary for the escapement disk 99 to make a complete revolution and carry lug 125 around to the rear of arm 127 before the circuit is broken. In the same way a second revolution of the arm 127 would bring lug 125 to the rear of lug 123 and two revolutions of the escapement wheel would be required.

25 As before stated, escapement wheel 99 is operated through anchor 100 which is in turn operated by cam 102 and solenoid 106. Referring to the wiring diagram shown in Fig. 14, switch 118 is shown as controlling the solenoid 56, which is disposed within the housing for the turnstile operating mechanism. Switch 66 disposed in the turnstile operating mechanism controls the solenoid 106 through contacts 60 and 70 and the motor 61 through contacts 68 and 69. It will be noted that solenoid 106 is so arranged in the circuit that both switches 118 and 66 must be closed in order to energize the solenoid 106 and the closing of switch 118 alone energizes solenoid 56.

30 Referring particularly to Fig. 11, assume that the link 95 was operated by the cashier to move the storing disk in a clock-wise direction for one tooth. This will move the arm 127 forward and permit the spring 122' to pull blade 121 into position to make contact between jaws 119 and 120, thereby closing switch 118. Referring particularly to Figs. 6, 7 and 8, closing of switch 118 energizes solenoid 56 at the turnstile, pulls arm 53, lifts the tail 41' of trailer 30' on arm 30 and a person who has paid the admission fee can then enter by pushing against arm 29. The arm is pushed forward by the entering person until it engages the arm on pintle 77, moves link 66' and closes the switch 66. Closing of the switch 66 energizes solenoid 106 and sets the motor 61 in operation. The motor rotates the disk 31 at the turnstile and causes the arm 29 to move forward, unlocking from the arm 30 after it has moved one quarter of a revolution, continue forward and locks the nose of its trailers 29' into the tail 41' of trailer 30'. As it reaches this point the arm on pintle 78 is moved, opening the switch 66 and stopping the motor. The roller 64 has traveled to the cut away portion of disk 26 where it stops. Closing of the switch 66 at the beginning of the movement of arm 29 energizes the solenoid 106, moves anchor 100

and permits the escapement disk to move one notch, thereby bringing arm 127 into contact with lugs 123 and 125 engaging ear 122, moving blade 121 and opening switch 118. Switch 118 being open, solenoid 56 is deenergized and the arms 30 and 29 are locked and no one can pass through until link 95 is again moved.

If two admissions have been stored up by 10 moving storing disk through two teeth, switch 118 will not be opened by one person passing through the turnstile as solenoid 106 would only be energized once allowing the escapement wheel to move one notch. This 15 will not cause arm 127 to engage lugs 125, 123 and ear 122; switch 118, therefore, remains closed and another person may pass through the turnstile. Upon the second person passing through solenoid 106 is energized, escapement disk 99 permitted to 20 move one more tooth and the switch 118 is opened by arm 127 engaging lugs 125 and 123 and ear 122 on blade 121, and the gate arms are locked against entrance of another.

We have shown an audible signal which 25 comprises a bell 130 mounted upon base plate 82. A tapper 131 is disposed with its end arranged to engage the bell. Tapper 131 is pivotally mounted upon lever 93, as indicated at 132. The extended arm 133 of 30 the tapper is arranged to engage spaced lugs 134 and 135 which may be integral with the lever 93. Lug 136 mounted on the plate 82 prevents the tapper from resting against 35 the bell 131. As the link 95 is moved upward and the upper arm of the bell crank 93 to the left, tapper 131 will be moved in a clock-wise direction and will strike the bell 130. As the bell crank 93 resumes its position 40 the tapper 131 comes in contact with lugs 136 keeping the tapper out of contact with the bell. Each movement of the link 95 and the storing up of one admission in 45 the gate control mechanism causes one tap on the bell 130.

In order to complete the mechanism within the turnstile we have provided segments of cylindrical surfaces which when spread form a complete cylindrical housing. These 50 segments are attached to the arms 29 and 30 and ride in tracks upon a closure plate 137 secured by a screw or other suitable means to plate 26, as particularly shown in Fig. 3. These tracks are in the form of grooves and 55 are oppositely disposed to similar grooves in the closure member 33. The segments are four in number and are indicated by 138, 139, 140 and 141.

To provide for the exit of persons from 60 the theater in case of fire or panic it is necessary that the arm 16 shown particularly in Figs. 1 and 2 be moved to a position at right angles to itself as indicated by the arrow —a— in Fig. 2. As the arm 16 on the 65 turnstile is swung outward it is necessary

that the rails 20 and 21 be swung to a position such that they will not obstruct the passageway and also that arm 30 be moved to a position parallel with the open position of rails 20 and 21.

Secured to the shaft 25 shown in Fig. 3 is a crank arm 142 and secured to the end of the crank arm is a rod 142' which is connected to a point eccentric to the axis about which arm 16 swings and is within the 75 housing 143, so that movement of the arm 16 will cause the shaft 25 to swing. As shaft 25 is keyed to disk 26 and plate 137 is fixedly secured to disk 26, the plate 137 will be rotated as arm 16 is swung. The 80 rails 20 and 21 are secured to the plate 137 and will, therefore, be rotated clockwise with respect to the arm 16, as the arm is swung inward. The construction is such that rails 85 20 and 21 will be in positions parallel to the arm 16 as the latter reaches a position at right angles to that shown in Fig. 2.

Arm 30 must also move into position parallel to rails 20 and 21 in order to permit arm 16 to swing fully open. Sleeve 27 90 is fixed to housing section 33 and carries fixedly secured to it a plate 28. Disk 26 is provided with a slot 144 through which extends a detent pin 145. Detent 145 is mounted on an arm 146 pivotally secured to disk 95 26 as indicated at 147. Arm 148 is off-set from arm 146 and is engaged by a spring 149 which is secured to the disk 26 and tends to maintain the arm 146 in such a position that detent 145 is at the inner end of the 100 slot 144. Plate 28 is provided with a notch 150 in its periphery, which normally registers with the slot 144. In normal position of the arm 16, detent 145 rests on the inner side of slot 144 and notch 150. Slots 144 105 and notch 150 are inclined so that as disk 26 is rotated with respect to plate 28, which occurs when the arm 16 is swung, the detent 145 will ride along the edge of the notch 150 and out to the periphery of plate 110 28 in which position the detent 145 is disposed to engage a pin on arm 30. Each arm has such a pin and the pin on arm 29 is indicated by 151. As arm 16 is swung open, pin 145 rides out of notch 150 to the 115 periphery of plate 28 and engages the pin on arm 30, thereby carrying arm 30 along with rails 20 and 21.

A counter of the cyclometer type is indicated at 152 and indicates the number of 120 times the gate is opened.

A switch 168 is disposed for convenient operation by the cashier. By opening the switch the gate turnstile arms will be locked. If any person without any right to enter 125 starts for the gate when it is unlocked for the entrance of a person, the cashier by opening switch 168 can lock the gate.

It is obvious that a person pushing upon the arm 16 from the inside will cause the 130

latter to swing around to a position at right angles to that shown in Fig. 2. The rails 20 and 21 will turn and arrange themselves parallel to the arm 16. The arm 30 will 5 also be moved into parallel position with the arm 16.

What we claim is:

1. A gate, comprising in combination two independently movable turnstile arms; 10 means automatically locking the leading and following arms during movement through a predetermined angle; and means to move the leading arm to a position as following arm after movement through said angle.
- 15 2. A gate, comprising in combination, a plurality of independently movable turnstile arms; a trailer on each arm, means on each of said trailers to automatically lock one trailer to another; a guide way for said trailers; means on said guide way to lock a trailer thereto; and means for releasing said locked trailer.
- 20 3. A gate, comprising in combination two independently movable turnstile arms; a trailer on each arm, means on said trailers to automatically lock a following trailer to a leading trailer; a guide way for said trailers, means on said guide way to lock a trailer thereto; said first named means and said second named means so arranged that locking of the trailers together will unlock the last mentioned trailer from the guide way, 25 means on said guide way to lock the second trailer thereto; and means for releasing said second trailer.
- 30 4. A gate, comprising in combination two independently movable turnstile arms; a trailer on each arm, each trailer provided with a nose and a tail, said noses and tails so arranged that the nose and tail of adjacent trailers will automatically lock; a guide way for said trailers, means on said guide way to catch one trailer; a second means on 35 said guide way to catch the second trailer, said noses and tails so arranged that locking of the nose of one trailer with the tail of the adjacent trailer will lift the latter trailer and release it from the first named means; and means for releasing said second trailer from said second means.
- 40 5. A gate, comprising in combination two independently movable turnstile arms; a trailer on each arm, each trailer provided with a nose and a tail, said noses and tails so arranged that the nose and tail of adjacent trailers will automatically lock, each tail having an inclined surface, each nose having an inclined surface to coöperate with 45 said first named inclined surfaces for lifting the tail, each of said tails provided with a depending catch; a guide way for said trailers, a recess on said guide way for a catch on one trailer, means on said guide way provided with a shoulder to engage the catch on

the second trailer; and means for lifting and 65 releasing the catch on the tail of said second trailer from said shoulder.

6. A gate, comprising in combination two independently movable turnstile arms; a trailer on each arm, each trailer provided 70 with a nose and a tail, each tail having an inclined surface and a locking lug, each nose having an inclined surface to coöperate with said first named inclined surface for lifting the tail, a notch in said nose forming a 75 keeper for said locking lug, each of said tails provided with a depending catch; a guide way for said trailers, a recess in said guide way for a catch on one trailer, means on said guide way provided with a shoulder to 80 engage the catch on the second trailer; and a movable member provided with an inclined face arranged to engage and lift the tail of said second trailer.

7. A gate, comprising in combination a 85 plurality of independently movable turnstile arms; a trailer on each arm, means on each of said trailers to automatically lock one 90 trailer to another; a guide way for said trailers; means on said guide way to lock a trailer thereto; means for releasing said locked trailer; mechanism for revolving said turnstile arms; a source of power for operating said mechanism; and means operated by 95 said arms for starting and stopping said mechanism.

8. A gate, comprising in combination a plurality of independently movable turnstile arms; a trailer on each arm, means on each of said trailers to automatically lock one 100 trailer to another; a guide way for said trailers; means on said guide way to lock a trailer thereto; means for releasing said locked trailer; a friction roller on each arm; a normally stationary disk with which said 105 rollers contact, said disk cut away so that the rollers will not contact therewith for a part of their revolution; a rotatable disk engaging said rollers to rotate the latter and revolve said arms; and a source of power 110 for operating said last named disk.

9. A gate, comprising in combination a plurality of independently movable turnstile arms; a trailer on each arm, means on each of said trailers to automatically lock one 115 trailer to another; a guide way for said trailers; means on said guide way to lock a trailer thereto; means for releasing said locked trailer; a friction roller on each arm; a normally stationary disk with which said 120 rollers contact; a rotatable disk engaging said rollers to rotate the latter and revolve said arms; a motor for operating said rotatable disk; and means operated by said arms for starting and stopping said motor.

10. The combination of a pivoted turnstile supporting arm adapted to swing horizontally; turnstile mechanism mounted thereon

- comprising two independently movable turnstile arms; means for locking the leading arm to bar a passageway; means to automatically position the following arm at substantially right angles to the leading arm; and mechanism arranged to move the following arm backward to a position parallel to said supporting arm upon movement of the latter. 11. The combination of a pivoted turnstile supporting arm adapted to swing horizontally; turnstile mechanism comprising two independently movable turnstile arms, said arms provided with detent engaging means; means for locking the leading arm to bar a 10 passageway; means to automatically position the following arm at substantially right angles to the leading arm; a pivoted member disposed adjacent said arms; means connected to said member and operated by swinging 15 of said supporting arm; a detent mounted on said pivoted member and normally disposed out of operative engagement with said detent engaging means; means to move said detent into operative position upon movement of said pivoted member and thereby move the following arm into a position parallel to said supporting arm upon swinging the latter at right angles to itself. 12. The combination of a pivoted turnstile supporting arm adapted to swing horizontally; turnstile mechanism mounted thereon comprising two independently movable turnstile arms, said arms provided with detent engaging means; means for locking the leading arm to bar a passageway; means to automatically position the following arm at substantially right angles to the leading arm; a shaft pivotally mounted on said supporting arm; a member fixedly secured to 20 said shaft; a detent mounted on said member for movement into and out of operative engagement with said detent engaging means; means for swinging said shaft operated by swinging of said supporting arm; and a detent operating member fixedly secured to 25 said supporting arm to move said detent into operative engagement with said detent engaging means when said supporting arm is swung. 13. The combination of a support; a turnstile supporting arm pivoted thereon adapted to swing horizontally; turnstile mechanism mounted thereon comprising two independently movable turnstile arms, said arms provided with detent pins; means for locking the leading arm to bar a passageway; means to automatically position the following arm at substantially right angles to the leading arm; a shaft pivotally mounted on 30 said supporting arm; a member fixedly secured to said shaft; a detent mounted on said member for movement into and out of operative engagement with said detent pins; means secured to said post eccentric thereto and to said shaft eccentric thereto; and a shaft eccentric thereto; and a 65 detent operating member fixedly secured to said supporting arm to move said detent into operative engagement with said detent engaging pins when said supporting arm is 70 swung. 14. The combination of a support; a turnstile supporting arm pivoted thereon and adapted to swing horizontally; turnstile mechanism mounted thereon comprising two independently movable turnstile arms, said 75 arms provided with detent pins; means for locking the leading arm to bar a passageway; means to automatically position the following arm at substantially right angles to the leading arm; a shaft pivotally mounted 80 on said supporting arm; a member fixedly secured to said shaft; a detent mounted on said member for substantially radial movement; means tending to hold said detent in its inward position; a disk disposed adjacent said member and fixedly secured to said supporting arm, said disk provided with an inclined notch in its periphery in which said detent is normally disposed, said disk having its periphery registering with said detent 85 pins; and means secured to said support eccentric thereto and to said shaft eccentric thereto. 15. The combination of a support; a turnstile supporting arm pivoted thereon and adapted to swing horizontally; turnstile mechanism mounted thereon comprising two independently movable turnstile arms, said arms provided with detent pins; means for locking the leading arm to bar a passageway; means to automatically position the following arm at substantially right angles to the leading arm; a shaft pivotally mounted 90 on said supporting arm; a disk fixedly secured to said shaft; a detent mounted on 95 said disk for substantially radial movement; a spring tending to hold said detent in its inward position; a sleeve pivotally mounted on said shaft and fixedly secured to said supporting arm; a second disk disposed adjacent said first disk and fixedly secured to said sleeve, said second disk provided with an inclined notch in its periphery in which said detent is normally disposed; said second disk having its periphery registering with said detent pins; and a crank arm fixedly secured to said shaft; means secured to 100 said crank arm and to said support eccentric thereto. 16. The combination of a support; a turnstile supporting arm pivoted thereon and adapted to swing horizontally; turnstile mechanism mounted thereon comprising two independently movable turnstile arms, said arms provided with detent pins; means for locking the leading arm to bar a passageway; means to automatically position the following arm at substantially right angles to the leading arm; a shaft pivotally mounted 105 on said supporting arm; a member fixedly secured to said shaft; a detent mounted on 110 said member for movement into and out of operative engagement with said detent pins; and a post eccentric thereto and to said shaft eccentric thereto. 17. The combination of a support; a turnstile supporting arm pivoted thereon and adapted to swing horizontally; turnstile mechanism mounted thereon comprising two independently movable turnstile arms, said arms provided with detent pins; means for locking the leading arm to bar a passageway; means to automatically position the following arm at substantially right angles to the leading arm; a shaft pivotally mounted 115 on said supporting arm; a member fixedly secured to said shaft; a detent mounted on said member for movement into and out of operative engagement with said detent pins; and a post eccentric thereto and to said shaft eccentric thereto. 18. The combination of a support; a turnstile supporting arm pivoted thereon and adapted to swing horizontally; turnstile mechanism mounted thereon comprising two independently movable turnstile arms, said arms provided with detent pins; means for locking the leading arm to bar a passageway; means to automatically position the following arm at substantially right angles to the leading arm; a shaft pivotally mounted 120 on said supporting arm; a member fixedly secured to said shaft; a detent mounted on 125 said member for movement into and out of operative engagement with said detent pins; and a post eccentric thereto and to said shaft eccentric thereto.

- to the leading arm; a shaft pivotally mounted on said supporting arm; a disk fixedly secured to said shaft; a detent mounted on said disk for substantially radial movement; 5 a spring tending to hold said detent in its inward position; a sleeve pivotally mounted on said shaft and fixedly secured to said supporting arm; a second disk disposed adjacent said first disk and fixedly secured 10 to said sleeve, said second disk provided with an inclined notch in its periphery in which said detent is normally disposed, said second disk having its periphery registering with said detent pins; a crank arm fixedly secured 15 to said shaft; means secured to said crank arm and to said support eccentric thereto; a guide rail; and means securing said guide rail to said shaft in a position normally at right angles to said supporting 20 arm.
17. The combination of a support; a turnstile supporting arm pivoted thereon and adapted to swing horizontally; turnstile mechanism mounted thereon comprising two 25 independently movable turnstile arms; said arms provided with detent pins; means for locking the leading arm to bar a passageway; means to automatically position the following arm at substantially right angles 30 to the leading arm; rollers on said turnstile arms; a shaft pivotally mounted on said supporting arm; a disk fixedly secured to said shaft; said disk in contact with said rollers; a detent mounted on said disk for substantially 35 radial movement; a spring tending to hold said detent in its inward position; a sleeve pivotally mounted on said shaft and fixedly secured to said supporting arm; a second disk disposed adjacent said first disk 40 and fixedly secured to said sleeve, said second disk provided with an inclined notch in its periphery in which said detent is normally disposed, said second disk having its periphery registering with said detent pins; a crank arm fixedly secured 45 to said shaft; means secured to said crank arm and to said support eccentric thereto; a third disk rotatably mounted on said sleeve and engaging said rollers to rotate the latter and revolve 50 said turnstile arms; a motor for operating said third disk; and means for starting and stopping said motor operated by said turnstile arms.
18. The combination of a support; a turnstile supporting arm pivoted thereon and adapted to swing horizontally; turnstile mechanism mounted thereon comprising two 55 independently movable turnstile arms; said arms provided with detent pins; a trailer on each arm, means on each of said trailers to automatically lock one trailer to another at substantially right angles to each other; a guide way for said trailers; means on said guide way to lock the following trailer 60 to the leading trailer for forward movement of the same; a guide way for said trailers, means on said guide way to lock the leading trailer thereto in a position substantially parallel to said supporting arm, said first named means and said second named means so arranged that locking of the trailers together will unlock the leading trailer from the guide way, means on said guide way to lock the following trailer thereto against forward movement; means for releasing said following trailers; rollers on said turnstile arms; a shaft pivotally mounted on said supporting arm; a disk fixedly secured to said shaft, said disk in contact with said rollers; a detent mounted on said disk for substantially 65 radial movement; a spring tending to hold said detent in its inward position; a sleeve pivotally mounted on said shaft and fixedly secured to said supporting arm; a second disk disposed adjacent said first disk and fixedly secured to said sleeve; said second disk provided with an inclined notch in its periphery in which said detent is normally disposed, said second disk having its periphery registering with said detent pins; a crank arm fixedly secured 70 to said shaft; means secured to said crank arm and to said support eccentric thereto; a third disk rotatably mounted on said sleeve.

and engaging said rollers to rotate the latter and revolve said turnstile arms; a motor for operating said third disk; and means for starting and stopping said motor operated by said turnstile arms.

20. The combination of a support; a turnstile supporting arm pivoted thereon and adapted to swing horizontally; turnstile mechanism mounted thereon comprising two independently movable turnstile arms; a trailer on each arm, means on said trailers to automatically lock a following trailer to a leading trailer for forward movement of the same; a guide way for said trailers; means on said guide way to lock the leading trailer thereto in a position substantially parallel to said supporting arm, said first named means and said second named means so arranged that locking of the trailers together will unlock the leading trailer from the guide way, means on said guide way to lock the following trailer thereto against forward movement; means for releasing said following trailer; rollers on said turnstile arms; a shaft pivotally mounted on said supporting arm; a disk fixedly secured to said shaft, said disk in contact with said rollers, a portion of said disk in the path of said rollers cut away; a detent mounted on said disk for substantially radial movement; a spring tending to hold said detent in its inward position; a sleeve pivotally mounted on said shaft and fixedly secured to said supporting arm; a second disk disposed adjacent the said first disk and fixedly secured to said sleeve, said second disk provided with an inclined notch in its periphery in which said detent is normally disposed, said disk having its periphery registering with said detent pins; a crank arm fixedly secured to said shaft; a link secured to said crank arm and to said support eccentric thereto; a third disk rotatably mounted on said sleeve and engaging said rollers to rotate the latter and revolve said turnstile arms; and a motor for operating said third disk.

21. An accumulator for turnstiles, comprising a storing member; means for moving said storing member progressively a unit; a discharge member movable in the same direction as said storing member; means to move said discharge member progressively a unit; control means interposed between said storing and discharge members normally in inoperative position and arranged to be disposed in operative position by relative movement of said discharge and control members one or more units.

22. An accumulator for turnstiles, comprising a storing member; means for advancing said storing member progressively by units; a movable discharge member; means for advancing said discharge member

progressively by units; an abutment member on said discharge member; a second abutment member on said storing member; and means controlling the operation of the turnstiles or the like operated by engagement of said abutment members.

23. An accumulator for turnstiles, comprising a storing member; means for advancing said storing member progressively by units; a movable discharge member; means for advancing said discharge member progressively by units; an abutment member fixed to said storing member; an abutment member movably secured to said discharge member; and a control switch operated by said abutment members.

24. An accumulator for turnstiles, comprising a storing disk; means for intermittently advancing said disk; a discharge disk; means for intermittently advancing said discharge disk; an abutment arm secured to said storing disk; a lever pivotally mounted on said discharge disk, and arranged to be moved by said abutment arm; and an electrical make and break device controlled by said lever.

25. An accumulator for turnstiles, comprising a storing disk provided with ratchet teeth; a pawl engaged therewith; a discharge disk provided with escapement teeth; an anchor engaged with said discharge disk; a motor spring secured to said discharge disk and to said storing disk; an abutment arm secured to said storing disk; a lever pivotally mounted on said discharge disk, said lever forming a blade of a switch; abutting means interposed between said lever and said abutment arm; and a jaw for said blade mounted on said discharge disk.

26. An accumulator for turnstiles, comprising a shaft; a storing disk provided with ratchet teeth mounted on said shaft; a pawl engaged with said storing disk; a discharge disk provided with escapement teeth rotatably mounted on said shaft; an anchor engaged with said discharge disk; a spiral spring secured at one end to said discharge disk and at the other to said storing disk; an abutment arm secured to said storing disk; a lever pivotally mounted on said discharge disk; said lever forming a blade of a switch; an abutting member pivotally mounted on said shaft and disposed to be engaged by said abutment arm and to engage said lever; and a jaw for said blade mounted on said discharge disk.

27. An accumulator for turnstiles, comprising a storing disk provided with ratchet teeth; a pawl engaged therewith; a discharge disk provided with escapement teeth; an anchor engaged with said discharge disk; a spiral spring secured at one end to said discharge disk and at the other end to said storing disk; an abutment arm secured to

- said storing disk; a lever pivotally mounted on said discharge disk, said lever forming a blade of a switch; abutting means interposed between said lever and said abutment arm; a jaw for said blade mounted on said discharge disk; collecting rings mounted on said discharge disk and brushes engaged with said collecting rings.
28. The combination of an accumulator, comprising a storing member; means for advancing said storing member progressively by units; a movable discharge member; means for advancing said discharge member progressively by units; an abutment member on said discharge member; a second abutment member on said storing member; control means operated by said abutment members; a gate comprising a locking mechanism operatively connected to said control means; an accumulator control mechanism operatively connected to said gate and to said means for advancing said discharge member to move the latter upon opening of said gate.
29. The combination of an accumulator, comprising a storing member; means for advancing said storing member progressively by units; a movable discharge member; means for advancing said discharge member progressively by units; an abutment member secured to said storing member; an abutment member movably secured to said discharge member; a switch operated by said abutment members; an electrical circuit controlled by said switch including a motor device; a gate, comprising a locking mechanism operated by said motor, an accumulator control mechanism operatively connected to said gate and to said means for advancing said discharge member to move the latter upon opening of said gate.
30. The combination of an accumulator, comprising a storing member; means for advancing said storing member progressively by units; a movable discharge member; means for advancing said discharge member progressively by units; an abutment member secured to said storing member; an abutment member movably secured to said discharge member; a switch operated by said abutment members; an electrical circuit controlled by said switch including a motor device; a gate comprising a locking mechanism operated by said motor; an electrical switch operated by said gate; an electrical circuit controlled by said last named switch and including a motor device, said last named motor device connected to said means for advancing said discharge member to control movement of the latter upon opening of the gate.
31. The combination of an accumulator, comprising a storing disk; means for intermittently advancing said disk; a discharge
- disk; means for intermittently advancing said discharge disk; an abutment arm moved by said storing disk; a lever pivoted on said discharge disk and disposed to be moved by said abutment arm; an electrical make and break device controlled by said lever; an electrical circuit controlled by said make and break device; a solenoid in said circuit; a gate, comprising a locking mechanism, said locking mechanism operatively connected to said solenoid, an accumulator control switch operatively connected to said gate; an electrical circuit controlled by said accumulator switch including a solenoid; and an anchor engaged with said discharge disk and operatively connected to the last named solenoid.
32. The combination of an accumulator, comprising a storing disk provided with ratchet teeth; a pawl engaged therewith; a discharge disk provided with escapement teeth; an anchor engaged with said escapement teeth; a spiral spring secured at one end to said storing disk and at the other end to said discharge disk; an abutment arm secured to said storing disk; a lever pivotally mounted on said discharge disk; said lever forming a blade of a switch; abutting means interposed between said lever and said abutment arm; a jaw for said blade mounted on said discharge disk; collecting rings mounted on said discharge disk; brushes engaged with said collecting rings; an electrical circuit connected to said brushes and including a solenoid; a gate, comprising a locking mechanism, said locking mechanism operatively connected to said solenoid; an accumulator control switch; an electrical circuit connected to said accumulator control switch and including a solenoid, said solenoid operatively connected to said anchor.
33. The combination of an accumulator, comprising a storing member; advancing means for said storing member to move the latter progressively by units; a movable discharge member; advancing means for said discharge member to move the latter progressively by units; an abutment member on said discharge member; a second abutment member on said storing member; a power control means operated by said abutment member; a gate comprising two independently rotatable turnstile arms; means to automatically secure the leading to the following arm during movement through a predetermined angle; means to move the leading arm to a position as following arm after movement through said angle; means to lock said arms against movement; release means to unlock said arms; mechanism for operating said release means; mechanism for operating the advancing means for said discharge member; a power transmission circuit including said

mechanism; a power control means in said transmission circuit operated by said turnstile arms at the completion of a revolution; and a branch power transmission circuit including the first named control means and said first named mechanism.

34. The combination of an accumulator, comprising a storing member; advancing means for said storing member to move the latter progressively by units; a movable discharge member; advancing means for said discharge member to move the latter progressively by units; an abutment member on said discharge member; a second abutment member on said storing member; an electrical switch operated by said abutment members; a gate comprising two independently rotatable turnstile arms; means to automatically secure the leading to the following arm during movement through a predetermined angle; means to move the leading arm to a position as following arm after movement through said angle; means to lock said arms against movement; release means to unlock said means to unlock said arms; a solenoid for operating said release means; a solenoid for operating the advancing means for said discharge member; an electric circuit including said solenoid; a switch in said circuit; means operated by said turnstile arms at the completion of a revolution for closing said switch; and a branch electric circuit including the first named solenoid and said first named switch.

35. The combination of an accumulator, comprising a storing member; advancing means for said storing member to move the latter progressively by units; a movable discharge member; advancing means for said discharge member to move the latter progressively by units; an abutment member on said discharge member; a second abutment member on said storing member; a power control means operated by said abutment members; a gate comprising two independently rotatable turnstile arms; means to automatically secure the leading to the following arm during movement through a predetermined angle; a motor mechanism to move the leading arm to a position as following arm after movement through said angle; means to lock said arms against movement; release means to unlock said arms; mechanism for operating said release means; mechanism for operating the advancing means for said discharge member; a power transmission circuit including said mechanism; a power control means in said transmission circuit operated by said turnstile arms at the completion of a revolution; a branch power transmission circuit including the first named control means and said first named mechanism; and a second branch power transmission circuit including said

motor mechanism and said second named control means.

36. The combination of an accumulator, comprising a storing member; advancing means for said storing member to move the latter progressively by units; a movable discharge member; advancing means for said discharge member to move the latter progressively by units; an abutment member on said discharge member; a second abutment member on said storing member; an electrical switch operated by said abutment members; a gate comprising two independently rotatable turnstile arms; means to automatically secure the leading to the following arm during movement through a predetermined angle; a motor mechanism to move the leading arm to a position as following arm after movement through said angle; means to lock said arms against movement; release means to unlock said arms; a solenoid for operating said release means; a solenoid for operating the advancing means for said discharge member; an electrical circuit including said solenoid; a switch in said circuit operated by said turnstile arms at the completion of a revolution; a branch electric circuit including the first named switch and said first named solenoid; and a second branch circuit including said motor mechanism and said second named switch.

37. The combination of an accumulator, comprising a storing member; advancing means for said storing member to move the latter progressively by units; a movable discharge member; advancing means for said discharge member to move the latter progressively by units; an abutment member on said discharge member; a second abutment member on said storing member; a power control means operated by said abutment member; a gate comprising a support; a turnstile supporting arm mounted thereon to swing horizontally; a turnstile mechanism mounted thereon comprising two independently rotatable turnstile arms; means to automatically secure the leading to the following arm during movement through a predetermined angle; means to move the leading arm to a position as following arm after movement through said angle; means to lock said arms against movement; release means to unlock said arms; mechanism for operating said release means; mechanism for operating the advancing means for said discharge member; a power transmission circuit including said mechanism; a power control means in said transmission circuit operated by said turnstile arms at the completion of a revolution; a branch power transmission circuit including the first named control means and said first named mechanism; detent engaging means

on said arms; a pivoted member disposed adjacent said arms; means connected to said member and operated by swinging of said supporting arm; a detent mounted on said pivoted member and normally disposed out of operative engagement with said detent engaging means; means to move said detent into operative position upon movement of said pivoted member and thereby move the

following arm into a position parallel to 10 said supporting arm upon swinging the latter at right angles to itself.

In witness that we claim the foregoing we have hereunto subscribed our names this 17th day of November, 1915.

ROBERT M. CAMPBELL.
LAWRENCE S. CAMPBELL.
